UNITED STATES PATENT OFFICE

HOWARD L. GALLOWAY, OF BALTIMORE, MARYLAND, ASSIGNOR TO LOCKE INSULATOR CORPORATION, OF BALTIMORE, MARYLAND, A CORPORATION OF MARYLAND

INSULATOR COTTER AND MODE OF USE

Application filed March 8, 1929. Serial No. 345,387.

The invention relates to insulators for high voltage transmission lines where it is customary to support a conductor from a support by means of an interposed string or 5 chain of insulator units. Each string or chain may consist of any desired number of units each of which usually comprises a dielectric body formed with an upstanding neck portion carrying a metal cap connected 10 with a pin embedded in and projecting from the underside of the unit next above. In the case of the uppermost unit the cap is of course connected with some suspension element carried by the stationary support from 15 which the string or chain is hung. In some cases the caps are provided with crevices which receive and which are pivotally connected with the pins of the adjacent units. However, the present invention has to do 20 with that type of insulator in which the cap is formed with a socket and an opening and in which the depending pin terminates in a more or less ball-like or otherwise curved head, the pin of each insulator being received 25 within the opening and the head being received within the socket in the insulator next below. When a plurality of such units are 30 assembled to form a string or chain, it is customary to provide a cotter pin which extends transversely through the cap and beneath the head of the pin therein so that if the units should move relatively, from some cause or 35 other, so as to result in canting of the pin, the pin cannot be disengaged from the cap as the head cannot be moved into such position as to pass through the opening communicating with the socket. In actual practice 40 cotter pins of various forms have been employed for this purpose with a greater or less degree of success, the great disadvantage being that when a cotter of ordinary pattern is retracted to permit disconnection of successive units, as for instance in case of a necessity for replacement of a unit, the cotter 45 may be withdrawn entirely from the cap and lost. In live line work the operation is generally carried out by means of long poles and it would be manifestly impossible by their use to replace a pin which has dropped out. 50 For clearness in explanation, reference

may be made to Patent No. 1,650,034 issued November 22, 1927 to D. H. Osborne and reference may also be made to the pending applications of D. H. Osborne Serial No. 33,538, filed May 28, 1925, and Serial No. 690,453, 55 filed February 4, 1924. A similar type of structure is also disclosed in the application of Bradford and Ritter Serial No. 488,203, filed July 28, 1921 and renewed October 13, 1925. 60

It is with the above set forth facts and conditions in view that I have devised the present invention which has for its general object the provision of a cotter for the purpose specified, or for an analogous use, which 65 after being once assembled with respect to the coacting elements will remain permanently attached thereto so as to be incapable of entire withdrawal, with possible resultant loss, except by the employment of special 70 tools which would deform it.

An important object of the invention is to provide a cotter of this character adapted and intended to be associated with an insulator cap in a novel manner, the reverse of 75 the usual procedure.

Another object of the invention is to provide means for distorting and spreading the cotter after it is in place so that it cannot be subsequently entirely removed except by the 80 use of a special tool.

An additional object of the invention is to provide a cotter which will be simple and inexpensive to manufacture, which may be quickly and easily associated with or applied 85 to an already existing insulator cap, which will be efficient and durable in service and also a general improvement in the art.

To the attainment of the foregoing objects 90 and advantages, the invention preferably consists in the detailed cotter pin construction and also in the detailed construction of a spreading means for the cotter to be hereinafter more fully described and claimed and 95 illustrated in the accompanying drawings in which:

Figure 1 is a side elevation of an insulator cap showing the novel cotter associated therewith and also showing the cotter spread- 100

ing device, the latter being partly broken away and in section,

Figure 2 is a front elevation of the spreading device alone,

5 Figure 3 is a plan view of the insulator cap showing the initial step involved in associating the cotter therewith with the cotter in its normal condition,

10 Figure 4 is a view similar to Figure 3 with the cotter moved into position ready for distortion to effect spreading of the arms thereof,

15 Figure 5 is a similar view showing the head of the cotter distorted as by means of the spreader shown in Figures 1 and 2, and

20 Figure 6 is a similar view showing the cotter in its final form and pushed into the position it will occupy when in actual use in an insulator string or chain.

25 Referring more particularly to the drawings, it will be observed that I have not shown a complete insulator unit as such would be entirely unnecessary to a proper disclosure of the invention especially in view of the introductory remarks supra, it being entirely sufficient that I have illustrated only the cap 1 such as is commonly used. This cap is of inverted cup-like form with an upwardly extending portion 2 of hollow form to define 30 a socket 3 with which communicate an opening 4 and a slot 5. The opening 4 is intended for the reception of the pin of the insulator next above, the head of the pin being received within the socket 3. Of course the slot 5 permits insertion of the pin and its head upon relative lateral movement of two units being assembled. At a point in alignment with the slot 5 and diametrically opposite the open end thereof there is provided a hole 6 for the 35 passage of the cotter indicated generally at 7 and to be described in detail hereinafter. Within the socket 3 it is preferable to provide spaced guide ribs 8 which are preferably inclined as shown in Figure 1. This feature is, however, not novel in the present application which has to do only with the cotter 7 and the mode of using the same. The guides 8 are not necessary and if they are provided the hole 6 must be of less width than the 40 space between them, as clearly indicated in Figures 3 to 6.

45 In carrying out the invention, the cotter pin 7 is formed from a single length of wire or other suitable material and is of general U-shape with its bight portion formed as an elongated loop shaped head 9 defined by crimping the arms 10 inwardly or toward each other as shown at 11. The arms 10 are shown as of equal length and have their free 50 ends directed outwardly or otherwise constructed to provide lateral projections 12. The exact manner of making the cotter is immaterial in so far as the present invention is concerned so long as it has the general 55 characteristics above set forth.

The mode of using the cotter is the reverse of the usual procedure in that, prior to the assembling of the insulator units in a string, each unit is equipped with a cotter which is inserted head first into the socket portion 3 of the cap so that the head 9 will pass from the socket through the hole 6 as shown in Figure 3. The cotter is then moved to project outwardly beyond the insulator cap as shown in Figure 4, the outward movement being limited by the engagement of the lateral extensions or projections 12 against the inner wall of the socket 3, as shown in Figure 4. It then becomes necessary to spread the head 9 so that its width will be increased to such an extent that it cannot pass back through the hole 6. Clearly, such spreading or distortion of the head may be accomplished by a hand tool or by means of a foot operated or power driven machine of suitable type, such as that illustrated in Figures 1 and 2.

20 Referring to Figures 1 and 2 in detail I have illustrated a spreading device comprising a suitable relatively stationary support 13, upon which is mounted a frame 14 including an upstanding portion 15 having a guide opening or channel 16 therethrough intersecting a transverse opening 17 of at least as great width as the desired width of the head 9 after the latter has been spread. 25 While variations may be resorted to, I have shown vertically movable guide rods 18 slideable through the frame 14 and support 13 and connected by a cross member 19 from which depends a plunger 20 slideable through the channel or bore 16. The extremity of this plunger is rounded and preferably of more or less cone shape as shown at 21 so that when forced through the head 9 it will distort the same and change its shape from the elongated form shown in Figures 3 and 4 to the widened form shown in Figures 5 and 6. Any suitable means may be provided for moving the plunger though in actual practice there may be provided a treadle or the like, not shown, 30 connected by a rod 22 with a cross member 23 carried by the lower ends of the guide rods 18. To effect retraction of the plunger after spreading of the cotter head I may provide a spring 24 surrounding the plunger and 35 abutting against a washer 25 thereon and against the top of the upstanding portion 15.

40 Assuming that the cotter has been inserted within the cap as above described, the head 9 is inserted through the opening 17 in the frame 14 of the spreading device and the plunger 20 forced downwardly, by whatever means is provided, so that it will enter and be forced through the head 9. As the plunger is of greater diameter than the inside width of the head the head will be spread laterally and will assume the form shown in Figure 5. The insulator unit is then ready for connection with others to form a string or chain. The depending headed pin of the unit in- 45

tended to be next above is inserted through the slot 5 so as to be disposed within the opening 4 with the head of the pin accommodated within the socket 3. The cot-
 5 ter 7 is then moved longitudinally from its projected position shown in Figure 5 into an inwardly extending position shown in Figure 6 so that the arms 10 will be disposed beneath the head of the pin
 10 carried by the unit next above. The lateral projections 12 at the free ends of the arms 10 ride along and against the confronting faces of the guide ribs 8 and it will therefore be apparent that the cotter cannot become dis-
 15 placed sideways. When the head of the pin is in its proper position within the socket 3 it is located close to the top surfaces of the ribs 8 and the highest portions of these ribs will prevent relative longitudinal movement
 20 of the pin and the cap 1. When the cotter 7 is moved to its innermost position, shown in Figure 6, it is apparent that the pin head cannot be withdrawn from the cap owing to the fact that the arms 10 are of substantially the
 25 same height or thickness as the thickest or highest portions of the ribs 8. The point is that it is obviously necessary to move the pin and cap relatively longitudinally of the pin in order to effect disconnection and this
 30 relative movement cannot occur when the cotter is in its final position. When the cotter is in its locking position the crimped portions 11 are located within the opening or hole 6 and the end walls of the hole engage within
 35 the depressions formed by the crimping so that the cotter cannot move accidentally.

With the construction above described, it is apparent that I have provided a cotter which will efficiently perform its function and
 40 which, when in locked position, cannot be removed except by the employment of a special tool for distorting it as the head is of greater width than the hole through which the cotter passes and as the arms have the outwardly
 45 extending lateral projections thereon. From the foregoing it is believed that the construction, mode of use and advantages will be readily apparent to one skilled in the art without further explanation.

50 While I have shown and described the preferred embodiment of the invention and a certain means for effecting spreading of the cotter, it should be understood that the disclosure is merely illustrative and that the
 55 right is reserved to make all such changes in the detailed construction of the cotter pin itself as well as in the construction of the spreading means therefor as will not depart from the spirit of the invention or the scope
 60 of the claims hereunto appended.

Having thus described the invention, I claim:

1. The method of applying a cotter to an insulator cap of the type having a socket for
 65 receiving a headed suspension member and

having the wall of the socket provided with a hole and the cotter being of general U-shape with an elongated head and arms joined thereto by a constricted portion, the head being of a width no greater than that of the 70 hole, said method comprising inserting the cotter head first through said hole from within the socket, and expanding the head to increase the width thereof beyond the width of the hole to prevent subsequent withdrawal 75 of the cotter through the hole.

2. The method of applying a cotter to an insulator cap of the type having a socket for receiving a headed suspension member and having the wall of the socket provided with 80 a hole and the cotter being of general U-shape with an elongated head and arms joined thereto having means thereon adapted to engage the wall of the socket, the head being of a width no greater than that of the hole; 85 said method comprising inserting the cotter head first through said hole from within the socket, and distorting the head to cause a portion thereof to overlie the hole for preventing subsequent withdrawal of the cotter 90 through the hole.

3. The method of applying a cotter to an insulator cap of the type having a socket for receiving a headed suspension member and having the wall of the socket provided with 95 a hole and the cotter being of general U-shape with an elongated head and arms joined thereto having means thereon adapted to engage the wall of the socket; said method comprising inserting the cotter head-first 100 through said hole from within the socket, and shaping the head to cause it to project beyond said hole for preventing subsequent withdrawal of the cotter through the hole.

In testimony whereof I affix my signature. 105
 HOWARD L. GALLOWAY.
